CLAIM

The ornamental design for a combined camera and wearable ring for holding a camera, as shown and described.

DESCRIPTION

FIG. 1 is a front side view of a combined camera and wearable ring for holding a camera showing my new design; FIG. 2 is a front view of the combined camera and wearable ring for holding a camera with the camera inside; FIG. 3 is a top view of the combined camera and wearable ring for holding a camera with the camera inside;

FIG. 4 is a top view of the combined camera and wearable ring for holding a camera shown without the camera to reveal aspects of the design that may not be apparent in other views;

FIG. 5 is a right side view of the combined camera and wearable ring for holding a camera with the camera inside; FIG. 6 is a right side view of the combined camera and wearable ring for holding a camera shown without the camera to reveal aspects of the design that may not be apparent in other views;

FIG. 7 is a left side view of the combined camera and wearable ring for holding a camera with the camera inside; FIG. 8 is a left side view of the combined camera and wearable ring for holding a camera shown without the camera to reveal aspects of the design that may not be apparent in other views;

FIG. 9 is a rear side view of the combined camera and wearable ring for holding a camera;

FIG. 10 is a perspective view of the combined camera and wearable ring for holding a camera;

FIG. 11 is a perspective view of the combined camera and wearable ring for holding a camera taken from the bottom shown without the camera to reveal aspects of the design that may not be apparent in other views; and,

FIG. 12 is a perspective side view of the combined camera and wearable ring for holding the camera positioned on a part of a human body.

The broken lines shown in the drawings represent environmental subject matter and form no part of the claimed design.

1 Claim, 8 Drawing Sheets
